(57) **CLAIM**

What is claimed is the ornamental design for an latch system for fitness apparatus, as shown and described.

DESCRIPTION

FIG. 1 is a front perspective view of an embodiment of the new latch system for fitness apparatus of Applicant's invention.

FIG. 2 is a side perspective view thereof.

FIG. 3 is a side view thereof.

FIG. 4 is a rear view thereof.

FIG. 5 is a front view thereof.

FIG. 6 is a top view thereof.

FIG. 7 is a bottom view thereof.

FIG. 8 is a front perspective view thereof illustrating the latch system for fitness apparatus with bench.

FIG. 9 is a side view of the latch system for fitness apparatus with bench.

FIG. 10 is a front perspective view of an additional embodiment of the latch system for fitness apparatus.

FIG. 11 is a rear perspective view of the additional embodiment of the latch system for fitness apparatus.

FIG. 12 is a side view of the additional embodiment of the latch system for fitness apparatus.

FIG. 13 is a rear view of the additional embodiment of the latch system for fitness apparatus.

FIG. 14 is a front view of the additional embodiment of the latch system for fitness apparatus.

FIG. 15 is a top view of the additional embodiment of the latch system for fitness apparatus.

FIG. 16 is a bottom view of the additional embodiment of the latch system for fitness apparatus.

FIG. 17 is a front perspective view of the additional embodiment of the latch system for fitness apparatus shown with a dip bar.

FIG. 18 is a side view of the additional embodiment of the latch system for fitness apparatus shown with a dip bar.

FIG. 19 is a front perspective view of another additional embodiment of the latch system for fitness apparatus.

FIG. 20 is a rear view perspective view another additional embodiment of the latch system for fitness apparatus.

FIG. 21 is a side view of another additional embodiment of the latch system for fitness apparatus.

FIG. 22 is a rear view of another additional embodiment of the latch system for fitness apparatus.

FIG. 23 is a front view of another additional embodiment of the latch system for fitness apparatus.

FIG. 24 is a top view of another additional embodiment of the latch system for fitness apparatus.

FIG. 25 is a bottom view of another additional embodiment of the latch system for fitness apparatus.

(Continued)

FIG. 26 is a front perspective view of another additional embodiment of the latch system for fitness apparatus with an exercise platform; and,

FIG. 27 is a side view of another additional embodiment of the latch system for fitness apparatus with an exercise platform.

The broken lines shown in the figures are for the purpose of illustrating portions of the latch system for fitness apparatus and form no part of the claimed design.
